UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,252,463.

Specification of Letters Patent.

Patented Jan. 8, 1918.

Application filed December 2, 1916. Serial No. 134,572.

To all whom it may concern:

Be it known that I, FRANK A. LUNDQUIST, a citizen of the United States, residing at New York, in the county of New York and State of New York, have invented certain new and useful Improvements in Telephone-Exchange Systems, of which the following is a full, clear, concise, and exact description.

10 This invention relates to telephone exchange systems, and has for its object a provision of means whereby the capacity of an automatic telephone system may be greatly increased without making the called numbers used therein unmanageable.

Such an object may be accomplished by using impulse senders of greater capacity than at present, whereby each digit of a telephone number may be selected in a greater 20 number of ways than at present, and by using selective switches of correspondingly increased capacity.

A feature of this invention is an impulse transmitter having a plurality of sets of positions, whereby the same train of impulses may be transmitted from corresponding positions in each of said sets of positions. This impulse transmitter is also provided with a circuit changing device whereby a 30 different circuit condition is set up in connection with each different set of positions to characterize such sets of positions, and differently effect the apparatus intended to receive such impulses.

Another feature of this invention is a selective switch arranged to serve a plurality of groups of lines in which the terminals of one group are periodically interspersed between the terminals of other groups.

Still another feature of this invention is the use of two line relays, one of which is marginal. The combined action of these two relays is the same during the sending of impulses from all positions of the impulse transmitter, but is different during the setting of such impulse transmitter in the different sets of positions. Through the different combined actions of these relays during the setting of the impulse transmitter a 50 group of lines in which the connection is desired is automatically selected.

The drawings disclose this invention in the form of a complete automatic telephone

system including in Figure 1 a calling subscriber's substation and a selector switch, 55 and in Fig. 2 a connector switch and a called subscriber's substation, all shown diagrammatically.

It is thought the invention may best be understood from the following detailed description of a complete cycle of actions in interconnecting two subscribers' substations.

In Fig. 1 a subscriber's substation S^1 is shown. In series with the line conductors of such a substation is an impulse transmitter I , which is arranged to send ten different series of impulses from two different sets of positions. In one set of positions impulses designated by the numerals 1 to 0, inclusive, may be sent, and in another set of 70 positions impulses designated by the letters A to J, inclusive, may be sent. The impulses sent from the position designated by the numeral 1 are the same as those sent from the position designated by the letter A, etc. 75 In one case, however, the subscriber's finger while setting such an impulse transmitter comes in contact with the stop s , and in the other case comes first in contact with the trigger t . The encounter with the trigger t 80 opens a contact 1, which introduces a resistance 2 in series with the line circuit. When the finger is removed from the finger hole in either case, the projections p strike an L-shaped member 3 and therethrough 85 cause the rapid opening and closing of the contact 4, which sends impulses of the well-known type. It is to be understood that the contact 1 is only opened while the impulse transmitter is being set and that through the 90 actual sending of the impulses such contact is closed.

Let it be assumed that the subscriber at substation S^1 has removed his receiver from its hook and that the call has been extended 95 in any well-known manner to the selector switch SS . A circuit is thereupon established from ground, battery, the winding of relay 5, first position contact and side-switch arm 6, the lower limb of the telephone line leading to the subscriber's substation S^1 , the contact 4, the contact 1, the transmitting apparatus of the subscriber's substation S^1 , the upper limb of the telephone line, the side-switch arm 7 and its first position contact, the winding of relay 8, to ground. The 100 105

relays 5 and 8 are energized in this circuit and as a result another circuit is established from ground, battery, the magnet Rel.¹, alternate contact and right-hand armature 5 of relay 5, to ground, through which this magnet is energized.

The release magnet Rel.¹, upon attracting its armatures, allows the cams 9 and 10 to make physical contact with the notches of 10 the vertical and rotary ratchets in such a manner as to prevent the switch from releasing from any set position.

At the same time a circuit is established from the ground, the upper pair of contacts 15 11 actuated by the magnet Rel.¹, conductor 12, thence through the test wire of a line switch (not shown) to well-known apparatus therein to prevent the release of such line switch.

20 The brushes b^1 , b^2 and b^3 secured to the shaft 13 of this selector switch are arranged to travel over and make contact with the terminals t^1 , t^2 and t^3 respectively. Such terminals are arranged in twenty levels of 25 ten contacts each, the even numbered levels of such contacts leading to one group of lines and the odd numbered levels of such terminals leading to another group of lines. The brushes b^1 , b^2 and b^3 are arranged to be 30 elevated two levels of such terminals upon each energization of the primary magnet PM¹, so that from the normal position the first energization of such primary magnet will bring the brushes in association with 35 the first level of the contacts and each subsequent energization will bring the brushes in association with each succeeding odd numbered level.

If, however, the magnet 14 is energized 40 previous to the energization of the magnet PM¹ the brushes b^1 , b^2 and b^3 will be elevated one step only, and, upon the first energization of the magnet PM¹, the brushes b^1 , b^2 and b^3 will be brought into association 45 with the second level of terminals t^1 , t^2 and t^3 , and each subsequent energization of the magnet PM¹ will elevate these brushes to a successive even numbered level of terminals.

Let it be assumed now that the subscriber's substation S¹ on the first setting 50 of the impulse transmitter I chooses the letter E. Upon so setting this impulse transmitter, the subscriber's finger coming in contact with the tripper t introduces the resistance 2 in the line circuit. Relay 8 is marginal, and due to the decreased current flow resulting from the opening of the contacts 1 deenergizes, but relay 5 still retains its energized position. A circuit is thereupon 55 established from ground to the contact and armature of relay 8, the left-hand armature and contact of relay 5, the vertical off-normal switch V.O.N., the winding of magnet 14, to battery and ground. The magnet 14 60 is energized and elevates the shaft 11 so

that the brushes b^1 , b^2 and b^3 will thereafter be driven in association with the even numbered levels of terminals.

It should be noted that the vertical off-normal switch does not open the circuit just 70 described until after this first movement is completed and the shaft may be retained in its actuated position by the pawl 9.

The subscriber now releases the impulse transmitter and in its operation four impulses are sent over the line. These impulses, as before described, consist in short openings of the line circuit whereby both relays 5 and 8 are intermittently deenergized and cause their armatures to vibrate rapidly. 80 The magnet Rel.¹ being slow to release is not affected by the intermittent break in its energizing circuit.

Upon each retraction of its armatures by relay 5, a circuit is established from ground, 85 the right-hand armature and normal contact of relay 5, the contacts 15 actuated by the magnet Rel.¹, the magnet PM¹, the first position contact and side-switch arm 16, the magnet Esc.¹, to battery, and ground. Magnet PM¹ responds to each impulse and thereby elevates the brushes b^1 , b^2 and b^3 to the desired level of terminals. The magnet Esc.¹, however, is energized by the first impulse and remains so energized until the last 95 impulse has been received. Upon its deenergization the side switch is escaped into the second position.

In the second position of the side switch a circuit is established between ground, the 100 contact and armature of magnet Esc.¹, rotary off-normal switch R.O.N.¹, side-switch wiper 17 and its second position contact, winding of magnet 18, to battery and ground. The magnet 18 is energized in this 105 circuit and completes another circuit from ground, armature and contact of relay 18, contact 15, winding of magnet SM¹, armature and contact of magnet SM¹, second position contact and side-switch arm 16, 110 winding of magnet Esc.¹, to battery, and ground. Magnets SM¹ and Esc.¹ are energized in this circuit. The magnet SM¹, however, attracts its armature and opens its own 115 energizing circuit and in this well-known manner causes the rotary movement of the brushes b^1 , b^2 and b^3 . At the end of the first rotary step a rotary off-normal contact R.O.N.¹ is opened and relay 18 depends for its energization upon circuit extending from 120 ground, battery, winding of magnet 18, the second position contact and side-switch wiper 17, the brush b^1 , the terminals t^1 , to the ground in the circuit of busy connector switches, in a manner to be described somewhat later. When the brush b^1 in its rotary movement encounters the terminal t^1 on which there is no ground, relay 18 is deenergized and in turn the circuits for magnets SM¹ and Esc.¹ are opened, whereupon 125 130

both of these magnets will retract their armatures.

The retraction of its armature by the magnet Esc.¹ escapes the side-switch wipers into the third position whereupon a circuit is established from ground, battery, the magnet Rel.¹, the third position contact and side-switch wiper 17, the brush b¹, the terminal t¹, and thence to ground which is placed thereon within the circuit of the seized connector switch before the magnet Rel.¹ can retract its armatures, in a manner also to be described somewhat later.

The movement of the side-switch wipers 6 and 7 into their third positions extends the line conductors from the subscriber's substation S¹ through the brushes b² and b³, terminals t² and t³, to the talking conductors of the connector switch CS. At the same time the control of the relays 5 and 8 is removed from the line and control of a similar pair of relays 20 and 21 is substituted. The immediate energization of relay 20 establishes a circuit from ground, the right-hand armature and alternate contact of relay 20, the side-switch wiper 22 in its first position, the conductor 23, the winding of magnet Rel.², to battery and ground. The connector switch release magnet is energized in this circuit and establishes another circuit for controlling the release of the selector switch SS¹ from ground, the left-hand armature and contact of magnet Rel.², the terminal t⁴, the brush b¹, and thence over the circuit previously described.

Let it be assumed in this case that the position of the impulse transmitter selected by the subscriber at the substation S¹ is that designated by the numeral 5. In this case the tripper t will not be touched and the contacts 1 will, therefore, not be actuated; in turn the relay 21 will remain energized and the circuit, which would otherwise be completed to energize the relay 24 similar in construction and action to relay 14, would not be energized. Upon the receipt of the five impulses sent by the impulse transmitter I, armatures of relays 20 and 21 will vibrate rapidly.

The release magnet in this case, as before, is slow to release and will not, therefore, be affected by the short breaks in its energizing circuit. During these breaks a circuit will be established from ground, right-hand armature and normal contact of relay 20, the right-hand armature and contact of relay Rel.², the winding of magnet PM², the first position contact and side-switch wiper 25, the winding of magnet Esc.² to battery, and ground. Through the actuation of the primary magnet the brushes b⁴, b⁵ and b⁶ are driven into association with the fifth odd numbered, or ninth level of terminals t⁴, t⁵ and t⁶.

It should be noted at this point that the

connector switch is provided with terminal sets leading to four hundred lines, arranged in twenty levels of twenty sets of contacts each, and that the terminals of one group of a hundred lines are periodically interspersed between the terminals of the other three groups of one hundred lines each in a manner similar to that heretofore described.

At the end of this series of impulses the escape magnet Esc.² deenergizes and causes the movement of the side-switch wipers of the connector CS to move into the second position:

Let it be assumed now that the subscriber at substation S¹ actuates the impulse transmitter from the position designated by the letter G. In this case, as in that first described, the contacts 1 will be opened in a manner similar to the previous case. The relay 21 will retract its armatures but relay 20 will not. A circuit is thereupon established from ground, contact of relay 21, the left-hand armature and contact of relay 20, the side-switch wiper 26 and its second position contact, the rotary off-normal switch R.O.N.², the winding of magnet 27, to battery and ground. The magnet 27 is energized in this circuit and actuates a pawl similar in construction to that actuated by the magnet SM¹ to drive the shaft of the connector switch one rotary step.

It should be noted in this case that the secondary magnet SM², like the primary magnets PM¹ and PM², is adjusted to drive the brushes over two sets of terminals at each step, so that now, when the impulses from the impulse transmitter I are received, the consequent intermittent energization of this magnet SM² rotates the brushes into the seventh even, or fourteenth rotary position of such brushes.

Should the line now engaged by the brushes b⁴, b⁵ and b⁶ be busy, such condition will be determined by the presence of a ground potential on the terminal t⁴, whereby a circuit will be established from ground, terminal t⁴, brush b⁴, side-switch wiper 28 and its second position contact, winding of relay 29, to battery and ground. Relay 29 attracts its armature and establishes a circuit from ground, the secondary of transformer T, the armature and contact of relay 29, the winding of magnet Esc.², to battery, and ground, whereby this escape magnet is prevented from moving the side-switch wipers into the third position. Through the interlinking of the primary and the secondary windings of the transformer T, a busy tone is induced in the circuit extending from ground, secondary of transformer T, the armature and contact of relay 29, the condenser C¹, the second position contact and side-switch wiper 30, the uppermost armature and contact of relay 32, and thence in the well-known manner over the

talking conductors of the connector switch CS, selector switch SS and the subscriber's substation S¹, whereupon the subscriber is informed of the busy condition of the desired line.

On the other hand, should the called line be idle, the escape magnet Esc.² will move the side-switch wipers into the third position, whereupon a circuit will be established 10 from ground, the right-hand armature and alternate contact of relay 20, the side-switch wiper 22 and its third position contact, the conductor 34, the armature and contact of tripping relay 35, the normal contact and 15 right-hand armature of relay 36, to a point where the circuit divides, leading in one direction through the winding of relay 32 to battery and ground, and in the other direction through the contact and left-hand 20 armature of relay 36 to the winding of relay Rel.² to battery and ground. Relay Rel.² is retained in its energized condition and relay 32 is energized in this circuit, whereupon the called subscriber's telephone bell 25 is rung through a circuit from a source of ringing current, the left-hand winding of relay 35, the alternate contact and inner armature of relay 32, side-switch wiper 31 in its third position the brush b⁵ and terminal t⁵, the called subscriber's telephone bell, 30 the terminal t⁶, the brush b⁶, the third position contact and side-switch wiper 30, the outer armature and alternate contact of relay 32 the right-hand winding of tripping relay 35 to the other pole of the source of 35 ringing current.

When the subscriber at substation S² in answer to the summons of his telephone bell removes his receiver from its hook, he places a path of such low resistance in the circuit just described that the current, which heretofore was not great enough to energize the relay 35, now becomes sufficient for this purpose, and relay 35 is energized. In attracting its armature, relay 35 removes a short circuit existing around the winding of relay 36 and consisting of a path from one side of this winding through the armature and contact of relay 35 and the normal contact and armature of relay 36 to the other side of this winding, and thereby places the winding of relay 36 in series with the winding of relay 32. Relay 36 is energized in this circuit and attracts its armatures, setting up for itself a locking circuit extending from ground, battery, alternate contact and right-hand armature of relay 36, the winding of relay 36, conductor 34, the third position contact and side-switch wiper 22, the alternate contact and right-hand armature of relay 20, to ground. The relay 32 is shunted by this circuit and deenergizes, whereupon it retracts its armatures and extends the talking conductors of the connector switch CS through to the called subscriber's substation S².

A circuit is now established from ground, battery, right-hand winding of relay 37, lower limb of the talking circuit the normal contact and inner armature of relay 32, side-switch wiper 31 and its third position contact, brush b^5 , terminal t^6 , through the apparatus and called subscriber's substation, terminal t^6 , brush b^6 , third position contact and side-switch wiper 30, outer armature and normal contact of the relay 32, the upper limb of the talking circuit, the left-hand winding of relay 37, to ground. The relay 37 attracts its armature and completes a circuit from ground, the right-hand armature and alternate contact of relay 20, the side-switch wiper 22 in its third position, armature and contact of relay 37, the conductor 28, release magnet Rel.², to battery and ground. 70 75 80

It should be noted that the circuit for the energizing of release magnet Rel.² was opened for a very short space of time during the interaction of the relays 35, 36 and 32, but relay Rel.² being slow to release did not retract its armatures before its energizing circuit was again completed by the action of relay 37.

Upon the movement of the side-switch wiper 28 into its third position, a ground was connected to the brush b^4 to characterize the seized line thereafter as busy, and at the same time to actuate the usual cut-off relay connected with such a line. 95

It will be noted that the control of the connection now resides in both subscribers, 100 for, should either hang up their receivers, the last described circuit for the energization of release magnet Rel.² will be opened at either one or the other of the two points controlled by the calling or called subscribers 105 respectively.

Let it be assumed in this case, that, when the conversation has been completed, the calling subscriber hangs up at practically the same time as the called subscriber. The energizing circuit for release magnet Rel.² will, therefore, be opened both at the alternate contact and right-hand armature of relay 20 and at the contact and **armature** of relay 37. The connector switch CS will be restored to its normal position and the removal of ground from the terminal t^2 , due to the retraction of its left-hand armature by the relay Rel.² will result in the deenergization of the magnet Rel.¹ of the selector switch SS, whereby this selector switch will also be restored to its normal position.

It should be noted in this type of switch, in which the release is accomplished by a backward rotary movement and then a downward vertical movement, that at the end of the rotary movement the rotary off-normal switch R.O.N.¹ is closed and the side-switch wipers are not restored to their normal position until the completion of 130

the vertical restoring movement. However, when the side-switch wipers were originally driven into the third position and the relay 5 was deenergized, a circuit was established from ground, the right-hand armature and normal contact of relay 5, the third position contact of side-switch wiper 16, winding of magnet Esc¹, to battery, and ground, whereby this magnet is energized until the side-switch wipers are finally restored to their original position. Therefore, when at the end of the rotary restoring movement the switch R.O.N.¹ is closed, the ground at the armature and contact of relay Esc¹ is prevented from reaching the winding of magnet Rel¹, which would thereby prevent the proper release of this switch.

While this invention has been described in connection with a full automatic telephone system it is not to be limited to such a system, but, since it may be applied with equal advantage to systems of other types, is to be limited only by the appended claims.

What is claimed is:

1. In a telephone system, groups of telephone lines, multi-group selective switches arranged to interconnect said lines, line terminals in said switches, the terminals of a group of lines being periodically interspersed between the terminals of other groups of lines, a set of brushes in each of said switches arranged to travel over and make contact with said terminals, impulse senders for setting said switches, a circuit changing device in said senders arranged to be operative only while said sender is being set in certain positions thereof, and control means for said switches responsive to said circuit changing device for causing said brushes to be set on terminals of a selected group of lines.

2. In a telephone system, groups of telephone lines, multi-group selective switches arranged to interconnect said lines, line terminals in said switches, the terminals of a group of lines being periodically interspersed between the terminals of other groups of lines, a set of brushes in each of said switches arranged to travel over and make contact with said terminals, and impulse senders arranged while being set to direct said brushes to a particular group of line terminals and while operating to direct said brushes to a particular set of terminals in said selected group.

3. In a telephone system, groups of telephone lines, multi-group selective switches for interconnecting said lines, line terminals in said switches, the terminals of a group of lines being periodically interspersed between the terminals of other groups of lines, a set of brushes in each of said switches arranged to travel over and make contact with said terminals, impulse senders arranged to be actuated from a plurality of

sets of positions, like trains of impulses being sent from corresponding positions in each of said sets of positions, a circuit changing device operable while said impulse transmitter is being set in any position of a particular set of positions, control means for said switches responsive to said impulse transmitters for setting said brushes on a particular set of terminals in any group of said terminals, and means responsive to said circuit changing device for setting said brushes within a particular group of said line terminals.

4. In an electrical switching system, groups of line circuits, multi-group selective switches arranged to interconnect said line circuits, line terminals in said selective switches, the terminals of a group being periodically interspersed between the terminals of other groups, a set of brushes in each of said selective switches arranged to travel over and make contact with said terminals, impulse senders for setting said switches, said impulse transmitters being provided with a circuit changing device arranged to be actuated while said impulse transmitters are being actuated, means for sending impulses while operating, and control means in said selective switches responsive in one manner to said circuit changing devices and in another manner to said impulses.

5. In a telephone system, telephone lines, substations connected to said lines each including an impulse transmitter, selective switches arranged to interconnect said lines, groups of line terminals in each of said switches, the terminals of one group being periodically interspersed between the terminals of other groups, a single set of brushes in each of said switches arranged to travel over and make contact with said terminals, and means controlled automatically by said substation impulse transmitter for determining which of said groups of terminals said brushes shall be directed to.

6. In a telephone system, groups of telephone lines, selective switches arranged to interconnect said lines, impulse transmitters to control said switches, line terminals in said switches linked to said lines, the terminals leading to one group of lines being periodically interspersed between the terminals leading to other groups of lines, a single set of brushes in each of said switches arranged to travel over and make contact with said terminals, and means controlled by said impulse transmitters for automatically directing the brushes of said switches to a particular group of said line terminals.

7. In a telephone system, groups of telephone lines, multi-group selective switches arranged to interconnect said lines, impulse transmitters for controlling said switches, fixed terminals in said switches linked to said telephone lines, the terminals of one

- group being periodically interspersed between the terminals of other groups, a single set of brushes in each of said switches arranged to travel over and make contact with 5 said terminals, means controlled by the operation of said impulse transmitter in one manner for selecting a set in a particular group of said terminals, and means controlled by the operation of said impulse 10 transmitter in another manner for selecting a corresponding set of terminals in another of said groups of lines.
8. In a telephone system, groups of telephone lines, multi-group selective switches 15 arranged to interconnect said lines, impulse transmitters for controlling said switches, fixed terminals in said switches linked to said telephone lines, the terminals of one group being periodically interspersed be- 20 tween the terminals of other groups, a single set of brushes in each of said switches arranged to travel over and make contact with said terminals, means controlled by a single operation of said impulse transmitter in one 25 manner for selecting a set in a particular group of said terminals, and means controlled by a single operation of said impulse transmitter in another manner for selecting a corresponding set of terminals in another 30 of said groups of lines.
9. In a telephone system, telephone lines arranged in groups, multi-group selective switches arranged to interconnect said lines, impulse transmitters for controlling said 35 switches, fixed terminals in each of said switches linked to said telephone lines, the terminals of one group being periodically interspersed between the terminals of other groups, a single set of brushes in each of 40 said switches arranged to travel over and make contact with said terminals, said impulse transmitter being provided with a circuit changing device operable while being actuated to direct said brushes into association with one or another of said groups of 45

line terminals, and means controlled by said impulse transmitters while operating to direct said brushes to a particular set of terminals in said selected group.

10. In a telephone system, groups of telephone lines, multi-group selective switches arranged to interconnect said lines, impulse transmitters, said switches being provided with a plurality of banks of fixed terminals and a set of brushes to travel over and make contact with said terminals, said impulse transmitter being arranged to operate from a plurality of sets of positions to send the same train of impulses in corresponding positions in each of said sets of positions, a circuit changing device included in said impulse transmitter arranged to be differently actuated in each of said sets of positions, and means controlled by said circuit changing device for causing said brushes to be set in association with one or another of said banks of terminals. 50 55 60 65

11. In a telephone system, groups of telephone lines, selective switches for serving a plurality of groups of lines each for interconnecting said lines, line terminals in said switches, the terminals of one group of lines being periodically interspersed between the terminals of other groups of lines, control circuits for said switches including a marginal relay, impulse transmitters for setting said switches arranged to send a plurality of sets of impulses from a plurality of corresponding sets of positions while operating, and also arranged to differently actuate said marginal relay while being set in each of said different sets of positions, whereby said switches may be set on a particular set of said terminals in a particular one of said groups of line terminals. 70 75 80 85

In witness whereof, I hereunto subscribe my name this 29th day of November A. D., 1916.

FRANK A. LUNDQUIST.
